UNITED STATES PATENT OFFICE.

LUKE HANNON, OF HENNESSEY, OKLAHOMA.

DEVICE FOR PROTECTING CRUDE-OIL TANKS.

1,229,261.

Specification of Letters Patent. Patented June 12, 1917.

Application filed May 16, 1916. Serial No. 97,851.

To all whom it may concern:

Be it known that I, LUKE HANNON, a citizen of the United States, residing at Hennessey, in the county of Kingfisher and 5 State of Oklahoma, have invented a new and useful Device for Protecting Crude-Oil Tanks, of which the following is a specification.

The present invention is a device for protecting a crude oil tank, and aims to provide 10 a novel and improved appliance to prevent the crude oil tank being destroyed by fire when it is struck by lightning or otherwise set on fire.

15 It is the object of the invention to provide means for automatically opening a closure of the tank in the event that the oil or other contents of the tank is set on fire, to enable the contents of the tank to be discharged 20 quickly to save the tank from injury.

It is also the object of the invention to provide a device of the nature indicated which is comparatively simple and inexpensive in construction, which can be readily 25 installed upon various oil and other tanks, and which is simple yet effective in operation.

With the foregoing and other objects in view which will appear as the description 30 proceeds, the invention resides in the combination and arrangement of parts and in the details of construction hereinafter described and claimed, it being understood that changes in the precise embodiment of the 35 invention herein disclosed can be made within the scope of what is claimed without departing from the spirit of the invention.

The invention is illustrated in the accompanying drawings, wherein: —

40 Figure 1 is an elevation of a tank embodying the present improvements.

Fig. 2 is a vertical section thereof, portions being broken away and others being shown in elevation.

45 Fig. 3 is a fragmental plan view of the device.

In the drawing, there is depicted a tank 1, such as is used for holding crude oil, but it is to be understood that the present improvements can be employed in various other tanks. The tank 1 is provided at one side and adjacent its bottom with an outlet opening 2 provided with a double closure embodying an outer door 3 hinged, as at 4, to the tank 1 at one side of the opening 2, and an inner door 5 mounted for vertical sliding

movement in suitable guides 6. When the door 5 is slid downwardly and the door 3 swung inwardly to closed position, this provides a double barrier against leakage. 60

Disposed at the upper edge of the tank 1 above the opening 2, is a pair of angular brackets 7 which are preferably secured upon an angle iron or other suitable support 8 attached to the tank adjacent its upper edge; and a flanged roller or spool 9 is mounted for rotation between and is supported by the brackets 7. Attached to the upper edge of the tank 1 diametrically opposite the spool 9 is a bracket 10 to which a 70 rope or other combustible or fusible element 11 is attached, and said rope 11 extends across the upper portion of the tank 1 toward and adjacent the spool 9. A chain or equivalent non-combustible element 12 is attached to the free end of the rope 11 and passes over the spool 9. Said chain 12 extends through and is attached to a weight 13, which weight is upon the exterior of the tank 1, being suspended from the spool 9 by 80 the chain 12. From the weight 13, the chain 12 passes back over the spool 9 and downwardly within the tank 1, and is attached to the upper end of the door 5. The rope 11 holds the chain 12 with the weight 13 in 85 suspended position, to prevent the weight 13 from falling, which if it occurs will raise the door to open position.

A latch 14 is pivoted, as at 15, to the outer surface of the door 3 and is swingable under a depending keeper 16 carried by the tank 1 adjacent the free edge of the door 3, whereby to hold the door 3 in closed position. A chain or other non-combustible flexible element 17 is attached to the free end of the latch 14 and is passed over the spool 9, being attached to the rope or cord 11. A suitable weight 18 is suspended from the latch 14, or can be attached to the lower end of the chain 17, and tends to swing the 100 latch 14 downwardly to releasing position. The rope 11 holds the chain 17 as well as the chain 12, whereby to hold the latch 14 in raised position behind the keeper 16.

As a means for holding the door 5 in 105 raised position, when it is open, a suitable spring catch 19 can be provided, to engage a notch 20 or other portion of the door 5 and hold it up.

Should the oil or other contents of the 110 tank 1 be ignited, the rope 11 will be immediately burned in two, thus releasing the

chains 12 and 17, which will permit the weights 13 and 18 to fall. The weight 13 in gravitating will pull the inner door 5 upwardly, which will be held raised by the spring catch 19, and the weight 18 in gravitating will swing the latch 14 downwardly away from the keeper 16, thus permitting the contents of the tank to swing the door 3 open. The tank will thus be immediately 10 emptied through the opening 2 to prevent the tank being injured by the conflagration. If desired, the oil or other fluid flowing from the opening 2 can be caught in a trough 21 to convey it from the tank 1 to 15 any suitable point. The device operates automatically, and even though simple and inexpensive in construction, it fulfills its office in a satisfactory manner.

Having thus described the invention, what 20 is claimed as new is:

1. The combination with a tank having a discharge opening, of an inner door closing said opening, means tending to open said door, an outer door closing said opening and 25 opening outward, means for holding the outer door in closed position, means tending to move the second mentioned means to releasing position, and combustible means for

30 preventing the first and third mentioned means from operating.

2. The combination with a tank having an outlet opening in one wall adjacent its bottom, of an inner sliding door closing said opening, an outer door hinged to the tank to close said opening and adapted to open 35 outwardly, guiding means carried by the tank adjacent its upper edge above said opening, a flexible element attached to the inner door and passing over said guiding means, a weight connected to said flexible 40 element to raise the inner door, a latch for holding the outer door in closed position, means tending to release said latch, a flexible element attached to the latch and extending over the guiding means, and a combustible element attached to the aforesaid 45 flexible elements, extending across and attached to the tank to normally prevent the doors from being opened.

50 In testimony that I claim the foregoing as my own, I have hereto affixed my signature in the presence of two witnesses.

LUKE HANNON.
